Application April 19, 1957, Serial No. 653,828

7 Claims. (Cl. 333—83)

The invention relates to a coupling device, and particularly to a coupling device in the form of an adjustable coaxial transmission line and tap for use with a transmission line section such as a coaxial resonant cavity.

An object of the invention is to provide an improved coupling device.

Another object of the invention is to provide an improved coupling device in the form of an adjustable coaxial transmission line and tap for use with a transmission line section.

Another object of the invention is to provide an improved coupling device that is in the form of a coaxial transmission line and tap, that is primarily designed to be used with a coaxial resonant cavity, and that can be adjusted to provide the desired loading to the resonant cavity over a wide range of operating frequencies.

The invention is primarily designed to be used with a coaxial resonant cavity having a hollow, cylindrical, outer conductor and a cylindrical inner conductor concentrically positioned within the outer conductor. Briefly, the invention provides means for adjusting the loading presented by a coaxial transmission line which is coupled to the coaxial resonant cavity. In accordance with the invention, the inner conductor of a section of coaxial transmission line is arranged so that it can be moved along its longitudinal axis with respect to the hollow outer conductor of the transmission line. The outer conductor of the coaxial transmission line section and the outer conductor of the coaxial resonant cavity are positioned so that they contact each other longitudinally along a joint wall portion for at least a portion of their respective lengths. Both outer conductors have a longitudinal slot in the joint wall portion to provide an opening between the resonant cavity and the transmission line section. A conductive connecting element or tap is fastened to the movable inner conductor of the transmission line section and extends radially from the movable inner conductor through the slot without touching the joint wall portion and without touching either of the outer conductors. The connecting element extends into the resonant cavity so that it contacts the inner conductor of the cavity over at least a portion of the movement of the inner conductor of the transmission line section. The point at which the connecting element contacts the inner conductor of the resonant cavity determines the loading presented to the resonant cavity by the transmission line section. In a preferred embodiment of the invention, an additional element is also provided to permit the resonant cavity to be frequency tuned. In addition to being used with a coaxial resonant cavity, the coupling device can also be used with coaxial transmission lines and with hollow wave-guides and cavities.

The invention is explained in detail in connection with the accompanying drawing, in which:

Fig. 1 shows a longitudinal view, partly in section, of a resonant cavity and a coupling device in accordance with the invention; and

Figs. 2 and 3 show transverse cross-sectional views taken along the lines 2—2 and 3—3, respectively, of the view shown in Fig. 1.

In the three figures, like reference numerals refer to like parts. The coupling device comprises a coaxial transmission line 10 having a hollow, metallic, cylindrical outer conductor 12, and a hollow metallic, concentric, cylindrical inner conductor 14. The outer conductor 12 of the transmission line 10 is arranged so that it is held in a stationary position. This transmission line 10 is intended to couple power from a coaxial resonant cavity 16 and apply this power to some load, not shown, such as an antenna. The inner conductor 14 of the transmission line 10 comprises a fixed portion 18 which extends within the outer conductor 10 towards the load, and a movable portion 20, one end of which is designed to telescope inside, as shown, or outside the fixed portion 18 of the inner conductor 14. At the other end of the movable portion 20 of the inner conductor 14, a metallic, connecting element or tap 22 is attached and electrically connected to the movable portion 20. This connecting element 22 extends radially from the movable portion 20 of the inner conductor 14 towards and into the resonant cavity 16.

25 The resonant cavity 16 comprises a hollow, metallic, cylindrical outer conductor 24, and a hollow, metallic, concentric, cylindrical inner conductor 26. The resonant cavity 16 is designed or dimensioned to be connected or coupled to an electron tube 28, such as an ultra high

30 frequency power amplifier tube like the RCA type 6448. Such a tube 28 is indicated in phantom in Fig. 1. The outer conductor 24 of the resonant cavity 16 is electrically and directly connected to the cathode electrode 30

35 of the tube 28 through a metallic flange 31 and a metallic ring 33. The inner conductor 26 of the resonant cavity 16 is directly and electrically connected to the anode electrode 32 of the tube 28. Thus radio frequency energy produced by the tube 28 is applied to the resonant cavity 16. The grid electrode 35 of the tube 28 is shown, but

40 the connections between the grid electrode 35 and the resonant cavity 16 are not shown since they do not relate to the invention. Suitable connections for a cooling fluid

45 may be placed in the hollow inner conductor 26 of the resonant cavity 16 and connected to the appropriate elements of the tube 28.

The transmission line 10 and the resonant cavity 16 are physically positioned so that their longitudinal axes are parallel, and so that their outer conductors 12, 24 are directly adjacent one another, and are directly joined or connected to each other at a common or joint wall portion. At this common or joint wall portion, a longitudinal slot 36 is placed in the joint wall portion to provide space for the connecting element 22 to move longitudinally. It is preferred that the slot 36 be as narrow or as small as possible so as to introduce as little discontinuity as possible into the resonant cavity 16 and the coaxial transmission line 10, and still provide clearance for the connecting element 22. In practice, it has been found that this discontinuity is, for all practical purposes, negligible. This is an important and desirable feature of the invention.

A coupling ring 38 is positioned within the resonant cavity 16. The coupling ring 38 comprises a cylindrical ring of metal that has a plurality of contacts or spring fingers 40 which are arranged and dimensioned to frictionally engage and contact substantially 360° of the outer surface of the inner conductor 26 of the resonant cavity 16. This coupling ring 38 is mechanically and electrically connected to the connecting element 22, which, in turn, is connected to the movable portion 20 of the inner conductor 14 of the transmission line 10. The

point at which the coupling ring 38, and hence the connecting element 22 contact the inner conductor 26 of the resonant cavity 16 determines the loading presented to the resonant cavity 16 by the transmission line 10. The coupling ring 38 only contacts the inner conductor 26 of the resonant cavity 16, and does not engage or contact the outer conductor 24 of the resonant cavity 16. The coupling ring 38 is moved longitudinally along or within the resonant cavity 16 by three metallic rods 42 which are connected to the coupling ring 38. The rods 42 are thus electrically connected to the inner conductor 26 of the resonant cavity 16. Consequently, it is unnecessary to insulate these rods 42 from the inner conductor 26, or to make them of an electrically insulating material. The rods 42 are spaced 120° apart, and extend longitudinally to a point at which they are connected to a suitable gearing arrangement 44 and a motor 46 for moving the rods 42. While three rods 42 are shown, more or less may be used. Furthermore, other arrangements, such as manual devices, can be used equally well to move the rods 42. As the rods 42 connected to the coupling ring 38 are moved longitudinally, the coupling ring 38 is also moved longitudinally, thus changing the loading presented to the resonant cavity 16. Likewise, the connecting element 22 and the movable portion 20 of the transmission line inner conductor 14 are also moved longitudinally. Thus, a practical and convenient means is provided for varying the loading on a coaxial resonant cavity.

A tuning ring 50 is also positioned in the resonant cavity 16. The tuning ring 50 comprises a cylindrical ring of metal that is designed and dimensioned to fit between the inner conductor 26 and the outer conductor 24 of the resonant cavity 16. The tuning ring 50 is provided with two sets of contacts or spring fingers 52 which frictionally engage or contact substantially 360° of the outer surface of the inner conductor 26 of the resonant cavity 16, and also frictionally engage or contact substantially 360° of the inner surface of the outer conductor 24 of the resonant cavity 16. The tuning ring 50 provides means for physically changing the physical size, and hence the resonant frequency, of the resonant cavity 16. The tuning ring 50 is moved by two rods 56 which are connected to the tuning ring 50. The rods 56 are spaced 180° apart, and extend longitudinally to a point at which they are connected to some suitable driving means, such as the gearing arrangement 58 and the motor 60. While two rods 56 are shown more or less may be used. Furthermore, other arrangements, such as a manual device, can be used equally well to move the rods 56. As the rods 56 are moved longitudinally, the tuning ring 50 is also moved longitudinally, thus changing the size and resonant frequency of the resonant cavity 16.

The end of the coaxial transmission line 10 nearest the electron device 28 is closed by a metallic plate 64 so as to provide an integral structure. Also, an insulator 66, such as a small disc of teflon, is fastened to the tuning ring 50 so as to prevent the connecting element 22 from being directly and electrically short-circuited to the tuning ring 50. This is desired so that if the tuning ring 50 and the coupling ring 38 are independently movable, it will not be possible to short-circuit the coupling ring 38 to the tuning ring 50. Any other suitable means of preventing this short circuit can also be used, thereby eliminating the teflon disc.

While not necessary, it is also possible to combine the driving arrangements, namely the gearing arrangements 44, 58 and the motors 46, 60, to provide a differential type of driving arrangement that permits both the coupling ring 38 and the tuning ring 50 to be moved simultaneously when the resonant frequency of the resonant cavity 16 is changed, and that permits the coupling ring 38 and the tuning ring 50 to be moved independently. Thus, it is possible to maintain the loading presented to the coaxial resonant cavity relatively constant despite changes

in operating frequency. This feature permits easy and rapid adjustment of the device.

While the coupling device has been described in detail in connection with a coaxial resonant cavity, it can be used equally well with a coaxial transmission line. Furthermore, the coupling device can also be used with a cavity, such as a hollow, cylindrical cavity, or with a waveguide. However, in the case of a hollow cavity or waveguide, it would not be necessary to use a coupling ring, as there would be no inner conductor to engage. The coupling device would serve as a probe in such an application.

The coupling device in accordance with the invention provides a novel means for coupling energy to a transmission line or similar structure under a wide variety of operating conditions and over a wide range of frequency tuning.

What is claimed is:

1. A coupling device for a hollow transmission line having at least an outer conductor, comprising a transmission line section having an outer conductor and an inner conductor positioned within said outer conductor of said transmission line section, said inner conductor of said transmission line section being arranged for movement along its longitudinal axis with respect to said outer conductor of said transmission line section, said outer conductor of said hollow transmission line and said outer conductor of said transmission line section being positioned so that said outer conductors contact each other along a joint wall portion for at least a portion of their respective lengths, said outer conductors each having a longitudinal slot therein at said joint wall portion, said slots registering with each other, and a rigid conductive connecting element fixedly fastened to one end of said inner conductor of said transmission line section and positioned so that it passes through said slots and into said hollow transmission line without touching said joint wall portion and said outer conductors over at least a portion of said movement.
2. A coupling device for a coaxial element having an outer conductor and an inner conductor symmetrically positioned within said outer conductor, comprising a transmission line having an outer conductor and an inner conductor symmetrically positioned within said outer conductor of said transmission line along the longitudinal axis of said transmission line, said inner conductor of said transmission line being arranged for movement along said longitudinal axis with respect to said outer conductor of said transmission line, said outer conductor of said coaxial element and said outer conductor of said transmission line being positioned so that said outer conductors contact each other along a joint wall portion for at least a portion of their respective lengths, said outer conductors each having a longitudinal slot therein at said joint wall portion to provide an opening between said coaxial element and said transmission line, a rigid conductive connecting element fixedly fastened to one end of said movable inner conductor of said transmission line and positioned so that it passes through said opening and into said coaxial element without touching said joint wall portion and said outer conductors, and a metallic coupling element connected to said connecting element within said coaxial element and positioned so that it is movable and contacts said inner conductor of said coaxial element over at least a portion of said movement of said inner conductor of said transmission line.
3. A coupling device for a coaxial element having a cylindrically shaped outer conductor and a cylindrically shaped inner conductor concentrically positioned within said outer conductor, comprising a transmission line having a metallic, cylindrically shaped outer conductor and a metallic, cylindrically shaped inner conductor concentrically positioned within said outer conductor of said transmission line, said transmission line inner conductor comprising a fixed portion and a telescoping movable

portion arranged for movement along its longitudinal axis with respect to said fixed portion of said inner conductor, said outer conductor of said coaxial element and said outer conductor of said transmission line being positioned so that their longitudinal axes are parallel and so that said outer conductors contact each other along a joint wall portion for at least a portion of their respective lengths, said outer conductors each having a longitudinal slot therein at said joint wall portion to provide an opening between said coaxial element and said transmission line, a rigid conductive connecting element fixedly fastened to the free end of said movable portion of said inner conductor of said transmission line and positioned so that it passes through said opening and into said coaxial element without touching said joint wall portion and said outer conductors, a metallic coupling ring connected to said connecting element and positioned around said inner conductor of said coaxial element, said coupling ring being movable and arranged so that it contacts said inner conductor of said coaxial element over at least a portion of its movement, and means connected to said coupling ring for moving said ring in a direction parallel to said longitudinal axis of said coaxial element.

4. A coupling device for a coaxial resonant cavity having a hollow cylindrical outer conductor and a cylindrical inner conductor concentrically positioned within said outer conductor, comprising a transmission line having a hollow, metallic, cylindrical outer conductor and a hollow, metallic, cylindrical inner conductor concentrically positioned within said outer conductor of said transmission line, said inner conductor of said transmission line having a fixed portion and a telescoping movable portion arranged for movement along its longitudinal axis with respect to said fixed portion, said outer conductor of said cavity and said outer conductor of said transmission line being positioned so that the longitudinal axes of their outer conductors are parallel and so that said outer conductors contact each other along a joint wall portion for at least a portion of their respective lengths, said outer conductors each having a longitudinal slot therein at said joint wall portion to provide an opening between said cavity and said transmission line, a metallic coupling ring positioned around said inner conductor of said cavity and arranged to be movable and to engage the outer surface of said inner conductor of said cavity, said coupling ring being dimensioned so that it is spaced from said outer conductor of said cavity, and a metallic connecting element fixedly fastened to the free end of said movable portion of said inner conductor of said transmission line and to said coupling ring, said connecting element being positioned so that it passes through said opening without touching said joint wall and said outer conductors.

5. A coupling device for a coaxial resonant cavity having a hollow cylindrical outer conductor and a cylindrical inner conductor concentrically positioned within said conductor, comprising a transmission line having a hollow, metallic, cylindrical outer conductor and a metallic, cylindrical inner conductor concentrically positioned within said outer conductor of said transmission line, said inner conductor of said transmission line having a fixed portion and a telescoping movable portion arranged for movement along its longitudinal axis with respect to said fixed portion, said outer conductor of said cavity and said outer conductor of said transmission line being positioned so that the longitudinal axes of their outer conductors are parallel and so that said outer conductors contact each other along a joint wall portion for at least a portion of their respective lengths, said outer conductors each having a longitudinal slot therein at said joint wall portion to provide an opening between said cavity and said transmission line, a metallic coupling ring positioned around said inner conductor of said cavity and arranged to be movable and to engage the

outer surface of said inner conductor of said cavity, said coupling ring being dimensioned so that it is spaced from said outer conductor of said cavity, a metallic connecting element fixedly fastened to the free end of said movable portion of said inner conductor of said transmission line and to said coupling ring, said connecting element being positioned so that it passes through said opening without touching said joint wall and said outer conductors, and means connected to said coupling ring for moving said coupling ring in a direction parallel to said longitudinal axis of said cavity.

6. In combination, a coaxial resonant cavity having a hollow, metallic, cylindrical outer conductor and a metallic, cylindrical inner conductor concentrically positioned within said outer conductor, and a coupling device for said cavity, said coupling device comprising a transmission line having a hollow, metallic, cylindrical outer conductor and a metallic, cylindrical inner conductor concentrically positioned within said outer conductor of said transmission line, said inner conductor of said transmission line having a fixed portion and a telescoping movable portion arranged for movement along its longitudinal axis with respect to said fixed portion, said outer conductor of said cavity and said outer conductor of said transmission line being positioned so that the longitudinal axes of their outer conductors are parallel and so that the outer surfaces of said outer conductors contact each other along a joint wall portion for at least a portion of their respective lengths, said outer conductors each having a longitudinal slot therein at said joint wall portion to provide an opening between said cavity and said transmission line, a movable metallic coupling ring positioned around said inner conductor of said cavity and having a plurality of spring fingers adapted to engage the outer surface of said inner conductor of said cavity, said coupling ring being dimensioned so that it is spaced from said outer conductor of said cavity, a metallic connecting element fixedly fastened to the free end of said movable portion of said inner conductor of said transmission line and to said coupling ring, said connecting element being positioned so that it passes through said opening without touching said joint wall and said outer conductors, and means connected to said coupling ring for moving said coupling ring in a direction parallel to said longitudinal axis of said cavity.

7. In combination, a coaxial resonant cavity having a hollow, metallic, cylindrical outer conductor and a metallic, cylindrical inner conductor concentrically positioned within said outer conductor, and a coupling device for said cavity, said coupling device comprising a transmission line having a hollow, metallic, cylindrical outer conductor and a metallic, cylindrical inner conductor concentrically positioned within said outer conductor of said transmission line, said inner conductor of said transmission line having a fixed portion and a telescoping movable portion arranged for movement along its longitudinal axis with respect to said fixed portion, said outer conductor of said cavity and said outer conductor of said transmission line being positioned so that the longitudinal axes of their outer conductors are parallel and so that the outer surfaces of said outer conductors contact each other along a joint wall portion for at least a portion of their respective lengths, said outer conductors each having a longitudinal slot therein at said joint wall portion to provide an opening between said cavity and said transmission line, a movable metallic coupling ring positioned around said inner conductor of said cavity and having a plurality of spring fingers adapted to engage the outer surface of said inner conductor of said cavity, said coupling ring being dimensioned so that it is spaced from said outer conductor of said cavity, a metallic connecting element fixedly fastened to the free end of said movable portion of said inner conductor of said transmission line and to said coupling ring, said connecting element being positioned so that it passes through said

opening without touching said joint wall and said outer conductors, a metallic tuning ring positioned between said inner conductor and said outer conductor of said cavity and having a plurality of spring fingers adapted to engage the outer surface of said inner conductor and the inner surface of said outer conductor of said cavity, and means connected to said coupling ring and to said tuning ring for moving said rings in a direction parallel to said longitudinal axis of said cavity.
